(57) **CLAIM**

The ornamental design for a vehicle hitch-cover cargo rack, as shown and described.

DESCRIPTION

FIG. 1 is a top plan view of a vehicle hitch-cover cargo rack attached to a trailer hitch receiver. The vehicle trailer hitch is shown in broken lines for illustrative purposes only and forms no part of the claimed design.

FIG. 2 is a front elevational view thereof,

FIG. 3 is a bottom plan view thereof,

FIG. 4 is a rear elevational view thereof having attached a centered reflector,

FIG. 5 is a right side elevational view thereof; and,

FIG. 6 is a left side elevational view thereof.
